(57) **CLAIM**

The ornamental design for a tub drain stopper, as shown and described.

DESCRIPTION

FIG. 1 is a top perspective view of a tub drain stopper, showing my new design;

FIG. 2 is a rear, bottom perspective view thereof;

FIG. 3 is a left, bottom perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The dashed broken lines in the figures illustrate portions of the tub drain stopper that form no part of the claimed design.
